UNITED STATES PATENT OFFICE.

EDWARD RUSSELL-CLARKE, DECEASED; BY FRANCES MAUD RUSSELL-CLARKE, EXECUTRIX, OF LONDON, ENGLAND, ASSIGNOR TO AUTOKAL SYNDICATE LIMITED, OF LONDON, ENGLAND.

CALCULATING MACHINE.

Application filed December 9, 1919. Serial No. 343,629.

To all whom it may concern:

Be it known that I, Mrs. FRANCES MAUD RUSSELL-CLARKE, a subject of the King of Great Britain, and residing at London, in England, sole executrix of EDWARD RUSSELL-CLARKE, late a subject of the King of Great Britain, who invented certain new and useful Improvements in Calculating Machines, of which the following is a specification.

10 This invention relates to calculators more especially for performing multiplication and of the type in which complex sums can be done in order to ascertain for example the total cost of a number of articles of which 15 the individual price is known.

According to this invention the calculator comprises a series of members each constructed and movable parallel to itself in two directions at right angles into positions 20 which are determinable by the setting up of one or a pair of stops so that the member will indicate a product, the amount of these products being ascertained and added by mechanism which presents the total. The 25 stops for positioning the product members are selected and set up by mechanism actuated by denominational selecting and numeral keys the latter being operative only as and when determined by the part of this 30 mechanism which is actuated by the selective keys. Thus until one or other of the denominational selecting keys has been operated the movement of a numeral key will produce no effect in the machine and even 35 after the numeral keys have been rendered "alive" by the operation of a selecting key the numeral keys will only remain in that state while they are used for performing operations the extent of which are determined 40 by the action of the selecting keys.

The machine may be said to comprise the following parts:—

1. The selective mechanism controlled by the denominational selecting and numeral keys.
2. The product plates which are positioned by the stops set up by the keys in accordance with the sum to be performed by the machine.
3. The adding mechanism by which the several products are collected and result presented.
4. The actuating mechanism by means of which when the keys have been depressed in

order to feed into the machine the necessary data the various parts of the machine are caused to perform their several functions so as to produce the desired result.

The chief features in these several parts may be briefly enumerated as follows:—

The principal feature of the selective mechanism is a series of longitudinally movable stop setting rods whose ends are all grouped like a chess-board in rows parallel in two directions and in one plane. A series of knives face the ends of these stop setting rods and each knife by the depression of a numeral key is reciprocated towards and between the grouped ends of the setting rods whose ends can be shifted in rows at right angles to the knives so as to bring the ends of all the rods in a selected row into the paths of the knives. The selecting of the rows of setting rods is effected by a series of cams mounted on a shaft to which rotation is imparted from a differentially actuated member the positioning of which is primarily determined by the denominational selecting and in a secondary sense by the numeral keys. An escapement controls the movement of the differentially actuating member and the rotation of the cam shaft. Rods similar to the stop-setting rods and constituting an inhibiting device can have their ends set out into the path of a knife by the action of certain cams on the cam shaft. Since the operation of these cams also is controlled by the denominational selecting keys the latter determine the ultimate result attained by the depression of the numeral keys even after the stop-setting rods have been positioned so as to be acted on by the key knives.

The number of product plates employed depends on the capacity of the machine. These product plates are conveniently disposed in two groups each plate being provided with V-shaped guides by means of which it is positioned by the stops set up in accordance with the value represented by these stops. The general construction and operation of the product plates is as described in the specification of United States of America Letters Patent No. 1,088,207. Each plate is arranged so that it can move parallel to itself in two directions at right angles into any position determined by the stops set up. Each plate carries a mechani-

cal representation of the products obtainable from that plate in the form of a series of pins the length of which is a measure of the value of a product.

- 5 The general construction and operation of the adding mechanism is as described in the specification of United States of America Letters Patent No. 1,075,003. It comprises several units each of which is composed of 10 a series of pulleys over which passes a flexible tape or the like of which one end is fixed while the other end is connected to a template which can rotate or move into a position determined by the extent to which 15 the tape is pulled or let out by the movement of one or more of the pulleys. In the present invention each pulley is connected to a device by means of which the length of a product pin is felt so that the pulley 20 makes a corresponding movement and thus the value of any product is transferred into the adding unit and the sum of these products in that unit is presented by the positioning of the template. The latter is conveniently in the form of a rotatable disc so 25 cut to correspond to the several integers with which that unit is to deal that the depth of the cutting or notches can be ascertained or felt by a finger which positions a number- 30 plate or equivalent accordingly.

The actuating mechanism is operated either by the movement of a hand lever or by the continuous rotation of a shaft by power. When the necessary denominational selecting and numeral keys have been depressed this mechanism is brought into action and first allows the product plates to be positioned in accordance with the stops set up and then permits the determined products to be felt and added in the adding mechanism and the result presented. Then during the second half of the cycle the product plates are returned to their initial or zero positions the adding mechanism 45 being also reset together with the number plates so that the machine is ready for the next operation. Conveniently there is a break in the performance of the complete cycle whether the mechanism is actuated by hand or power so that the sum performed by the machine can be read off before the parts are restored to their initial positions in readiness for the next operation.

55 In the accompanying drawings, Figure 1 is a front view of a portion of the machine showing the keys, key levers and part of the mechanism operated thereby.

Figure 2 is a side view of the same.

60 Figure 3 is a plan of the key-actuated escapement and the mechanism by which the cam shaft controlling the selective mechanism is rotated.

Figure 4 is a perspective view of this escapement on an enlarged scale.

65 Figure 5 is a front view showing the

principal part of the selective mechanism namely the "chess-board" arrangement of the ends of the setting rods and the cam shaft controlling them.

Figure 6 is a perspective view of certain 70 parts of the mechanism displayed to show the manner in which a positioning stop is set up by the depression of a key.

Figure 7 is a perspective view of parts 75 of the mechanism displayed to show the main and individual inhibiting stops and the manner in which they are withdrawn from action by key operation.

Figure 8 is a plan of the whole machine.

Figure 9 is an elevation of the right hand 80 side of the machine showing the principal parts of the mechanism by which it is actuated after the keys have been depressed.

Figure 10 is an elevation of the rear of 85 the machine.

Figure 11 is a plan showing a part of 90 the mechanism by which the rods for setting up the positioning stops are returned after operation and the stops reset.

Figure 12 is an elevation of the mechanism 95 by means of which the various products are added and the result presented, the mechanism appearing as it would be seen from the left hand side of the machine.

Figure 13 is a section on the line 13—13 100 of Figure 12 looking in the direction of the arrow and showing part of the mechanism illustrated in Figure 12.

Figure 14 is a plan of the group of cams 105 controlling the selective mechanism illustrated in Figure 5.

Figure 15 is a section on line 15—15 of Fig. 10;

Figures 16 and 16* when taken together 110 illustrate the machine in section on line 16—16 of Fig. 8;

Figure 17 is a sectional view showing in elevation one of the adding units as viewed from the left hand side;

Figure 18 is a section on line 18—18 of 115 Fig. 17;

Figure 19 is a view similar to Fig. 17, but illustrating the pence adding mechanism;

Figure 20 is a plan view of portion of the mechanism illustrated in Figs. 17 and 19;

Figure 21 is a perspective view of one of the cams with certain of the mechanism associated therewith;

Figures 22, 23 and 24 are perspective views 120 of the same cam shown in Fig. 21, but showing the cam in different positions and showing additional mechanism associated therewith.

Fig. 25 is a view similar to Fig. 17 showing the tens of shillings adding unit, and

Fig. 26 is a rear sectional view of part of the mechanism shown in Fig. 15, the section being taken on the line 26—26 of the figure.

Like letters indicate like parts throughout the drawings.

It will be convenient to deal in order with the several principal parts of the machine as indicated above taking first the selective mechanism and the manner in which it is controlled and operated. It may also be noted that the machine hereinafter described and illustrated is constructed and provided with the necessary keys to enable it to deal with any number of articles up to 99 at any price from one penny up to £9.19.11. It will be understood however that the machine may be constructed to have a larger capacity or if necessary to deal with other monetary systems or either weights or measures.

Referring first of all to Figures 1 and 2 the denominational selecting keys A are five in number and for convenience of reference in Figure 1 the figures or values of these respective keys are indicated in separate small circles placed over the respective keys, thus it will be noted that reading from the left hand side of Figure 1 the first selecting key serves either to operate selective mechanism with respect to unit articles or when dealing with the price with respect to unit pence. The second key similarly is employed for dealing with tens of articles or with respect to price with tens of pence. The third key is employed solely when dealing with price and relates to unit shillings. The fourth key also deals only with price and relates to tens of shillings. The fifth key deals solely with unit pounds. If the capacity of the machine is to be increased further similar denominational selecting keys would be added dealing respectively with tens of pounds and hundreds of pounds and so forth.

The numeral keys B are eleven in number and numbered from 1 to 9 running from the left hand side of Figure 1, with the two keys on the extreme right marked 0 and 10. It is to be noted that the latter are used solely when dealing with the prices of articles involving tenpence or elevenpence. This arrangement is a matter of convenience in the construction of the machine more particularly here described, but if necessary the machine can be arranged to be operated with ten keys numbered from 1 to 10.

Each denominational selecting key A is mounted on one end of a two-armed lever A' the other end of which lies adjacent to a differentially actuated member to be hereinafter described. The ends of these levers are severally designated A², A³, A⁵, A⁶, A⁷. All these levers A' are pivoted at A⁸. A rod C lies over or against all the lower lever arms A so that whenever a selecting key A is depressed and a lever A' is moved the rod C and the parts connected thereto will be moved. The rod C is carried by levers C' C² pivoted on the shaft A⁸ carried on fixed brackets B¹⁵. The arm C' is extended beyond the rod C and is connected at its end

C³ with a pawl forming part of an escapement to be hereinafter referred to.

Each numeral key B is mounted on one arm of a two-armed lever B' B² pivoted to a shaft B³ supported in fixed bracket B¹⁴. The shape and arrangement of the numeral key levers and the principal mechanism operated thereby is shown in Figures 6 and 7.

Beneath all the numeral key lever arms B' lies a rod B⁴ carried at its ends on two levers B⁵ pivoted on the axis B⁶. One of these levers B⁵ is provided with a second arm B⁶. The arrangement is such that whenever a numeral key lever B' is depressed this lever will strike the rod B⁴ and move the lever B⁵ B⁶. Against the front of each key lever arm B² lies a bar D carried on two levers D' D² pivoted to a shaft D³ carried in the brackets B¹⁵ which support the shaft A⁸ behind the shaft A⁸ on which the denominational selecting key levers A' are pivoted. One of these levers D' has a second arm D⁴ the end of which engages and operates pawls in the escapement to be hereinafter referred to. The arrangement is such that whenever a numeral key B is depressed the arm B² of the key lever will strike the bar D and move the lever D' D⁴.

The free end of each key lever arm B² is rounded and engages a recess in the end of the arm B⁷ of a two-armed lever pivoted on the shaft D³. The other arm B⁸ of this lever carries pivoted on the end thereof a vertically disposed knife-like member B⁹. The edge of this knife is directed inwards while a tail forked as at B¹⁰ engages a rod B¹¹. The arrangement is such that when a numeral key B is depressed the lever B⁷ B⁸ will be rocked and the knife B⁹ pushed forward, the fork B¹⁰ sliding on the rod B¹¹ and guiding the knife B⁹ so that it always remains vertical. The end of the lever B⁶ operated by the rod B⁴ lying beneath the numeral key levers is similarly rounded and engages a two-armed lever B¹² B¹³ also pivoted on the shaft D³. The lever B¹³ carries and operates a knife member B¹⁴ similar to the knife B⁹ the knife B¹⁴ being also guided by means of a forked tail B¹⁵ engaging the rod B¹¹. Each key lever arm B⁶ is acted on by a coiled spring B¹⁶ which is fixed at one end to a part B¹⁷ of the frame of the machine carrying the brackets B¹⁴ and B¹⁵, and tends to restore the key B to its normal position after depression and this spring also serves to keep the knives B⁹ and B¹⁴ in their withdrawn or inoperative positions.

A spring C⁵ fixed to a suitable part of the frame work of the machine acts on the bar C and a spring D⁷ fixed to the part B¹³ which holds the springs B¹⁶ acts on the bar D, these springs tending to keep these bars in the positions necessary for them to be acted on respectively by the tabulating key levers A and the numeral key levers B².

The differentially actuated member or plate E lies across the front of the machine as shown in Figure 1 and is so mounted that it can slide under the influence of a coiled spring which acts through a flexible tape or cord E' tending to draw the plate E to the right hand side of the machine. The upper edge of the differentially actuated plate E is provided with a series of notches or recesses 10 which form projections E², E³, E⁵, E⁶, E⁷, E⁸ and E⁹. The face of each of these projections as shown in Figure 3 is bevelled off to engage the correspondingly bevelled off ends of the tabulating levers A². Projecting horizontally from the back of the plate E is a portion E¹⁰ which carries a toothed rack E¹¹ disposed parallel to the plate E.

Rotatably mounted in suitable bearings is a vertical shaft F Figure 5. On this shaft 20 towards its lower end is a toothed pinion F' which gears with the rack E¹¹. Along the upper part of the shaft F are disposed in pairs a series of cams F² F³. On the lower end of the shaft conveniently below the pinion F' is a ratchet wheel G. This ratchet wheel (Figures 3 and 4) is provided with equally spaced teeth G', G², G³, G⁴, G⁵, G⁶, G⁷, G⁸, G⁹, all these teeth are similar when the ratchet wheel is viewed in plan but two 30 of these teeth G' and G⁴ are of greater width as shown in Figure 4. A bracket F⁴ which conveniently forms part of the lower bearing of the cam-shaft F carries pivoted on a stud F⁵ two pawls which constitute an escapement for controlling the rotation of the cam-shaft F. One of these pawls H is carried on a two-armed lever H' H². The other pawl J is carried on a two-armed lever J' J². The pawl H is of varying width 40 as shown in Figure 4 the dimensions being such that when the pawl is withdrawn sufficiently to clear one of the ordinary teeth such as G² G³ of the ratchet wheel the upper and wider part of the pawl H can still engage either of the wider teeth G' or G⁴. A spring H³ attached at one end to the bracket F⁴ and at the other to the pawl lever H' tends to maintain the pawl H in engagement with the teeth of the ratchet wheel G. The end of the lever C³ acted on by the tabulating levers A A² through the bar C is connected by a link C⁴ to a projection on the pawl lever H'. Thus movement 50 of the lever C³ consequent on the operation of a denominational selecting key will cause the pawl H to be withdrawn sufficiently to clear all the teeth of the ratchet wheel G, not merely the ordinary teeth such as G² G³, but those teeth G' G⁴ which as mentioned 60 have greater width. The lever D⁴ to which movement is imparted when a numeral key is operated has its end T-shaped, the cross-piece of this end forming arms D⁵ D⁶ which lie between the pawl-levers J' on the one hand and J² H² on the other. Thus when- 65 ever a key lever is operated the end of the lever D⁴ will move towards the ratchet wheel and in so doing the cross-piece D⁵ will move the pawl lever H² thereby lifting the pawl H sufficiently to clear one of the ordinary teeth such as G² G³ of the ratchet wheel G. The movement however is not sufficient to take the pawl H clear of either of the wider ratchet wheel teeth G' or G⁴. This movement of the lever D⁴ through the 70 arm D⁶ acting on the pawl lever J² also causes movement of the pawl J towards the ratchet wheel to an extent sufficient to cause this pawl to catch and engage either of the teeth of the ratchet wheel. On the return movement of the lever D⁴ when a key lever is released after operation, the arm D⁶ of the cross-piece bears against the pawl lever J' and withdraws the pawl J from engagement with the ratchet wheel. Simultaneously the pawl H is freed to again move towards the ratchet wheel and engage a tooth thereof. The pawls H and J are spaced apart a distance slightly greater than the distance between any two teeth of the 80 ratchet wheel so that when by the operation of a numeral key lever the pawl H is lifted clear of a tooth of the ratchet wheel G this ratchet wheel and the shaft F can only rotate to a slight extent being checked in its movement by the pawl J. On the return movement of the lever D⁴ as the pawl J is withdrawn from engagement with the ratchet wheel the pawl H descends on the inclined back of a tooth of the ratchet wheel 90 and slides down the back of this tooth until it engages the tooth next presented to it. The back of the pawl H is rounded as shown in Figure 4 to facilitate its sliding over the back of each tooth. 95

The projections on the differentially actuated plate E correspond to the rotary positions of the cam-shaft F as determined by the teeth of the ratchet wheel G and these positions bear definite relation to the sequence of operations performed when manipulating the denominational selecting and numeral keys for the purpose of performing a sum with the machine. The details of this relationship will be described after reference to the remainder of the selective mechanism. 105

A frame comprising two upright members F⁶ and two horizontal members F⁷ carries the cam shaft F by the lower bracket F⁴ and an upper bracket F⁸ in which the cam-shaft rotates. On the upright members F⁶ are disposed a series of equidistant studs or rollers F⁹ which constitute guides and bearings for a series of setting plate K K', L L', arranged in pairs, each plate L or L' being disposed behind a plate K or K'. These setting plates lie horizontally and radially with respect to the axis of the cam-shaft F and the end of each plate is provided 110

with a finger K^2 , L^2 opposed to a pair of cams F^2 , F^3 . The arrangement is such that as the cam-shaft rotates and according to the position occupied by it as determined by the teeth of the ratchet wheel G the cams F^2 , F^3 in each pair will be able to act on the fingers K^2 , L^2 and push the setting plates K , K' , L , L' laterally either in pairs or separately according to the formation of the cams. This lateral movement takes place against the action of springs (not shown in the drawings) bearing on the ends of the setting plates K , K' , L , L' remote from the cam-shaft so that as the latter rotates and the action of a cam on any particular plate ceases this plate will be restored to its initial position. The upper edge of each setting plate K is provided with a series of rectangular notches in each of which lies the squared end of a setting rod M . It will be seen from Figure 5 that in most of these plates K the number of notches and rods M carried thereby is nine but one of the setting plates towards the top of the group is provided with ten notches and carries ten rods M while a similarly notched plate with ten rods is disposed towards the bottom of the group. The uppermost and lowermost setting plates K' each have only two notches and carry two rods M^x and M^y situated towards the ends of the plate. Each setting plate L , L' is provided in its upper edge with a single rectangular notch disposed towards that end which is nearest to the cam-shaft. In the notch of each setting plate L' which as will be seen are the uppermost and lowermost of these plates there is carried the squared end of a setting rod N . In the notch of each intermediate setting plate L is carried the end of a setting rod N .

By longitudinal movement of the rods M stops are set up in a manner to be herein-after described by means of which the product plates are positioned. By longitudinal movement of the rods N and N' certain stops are withdrawn in a manner to be herein-after described these stops serving until withdrawn to prevent the product plates from being positioned and consequently to inhibit the effect of the longitudinal movement of the setting rods M . It will be seen from Figure 5 that the ends of all the setting rods are grouped like a chessboard in rows parallel in two directions and in one plane since the ends of the setting rods in one row are positioned directly under the ends of the setting rods in the row above.

On each of the horizontal members F^7 of the frame which carries the setting plates K is disposed a flange F^{10} which projects towards the front of the machine and in each flange is a series of forwardly directed slots F^{11} . The number of these slots corresponds to the maximum number of

notches, that is to say setting rods, in any one of the horizontal rows and the slots in the two flanges are vertically in line but positioned so that the vertical lines between these slots will pass between the vertical rows formed by the ends of the setting rods M , N , N' when the setting plates are in their normal positions of rest, that is to say in their limit positions towards the left hand side of the apparatus as shown in Figure 5. In the slots F^{11} lie the knives B^9 , B^{9x} , the latter occupying the two end slots F^{12} on the left hand side. Thus these notches F^{11} , F^{12} serve as guides for the knives in their reciprocating movement towards the setting plates and setting rods.

It will be seen that as the cam-shaft rotates the setting plates are severally shifted so as to throw the ends of the rods M , N , N' into the paths of the knives when these are reciprocated as a result of the depression of the numeral key levers. The setting plates K , K' , L , L' are relatively disposed in accordance with the arrangement of the product plates the positioning of which is determined by the stops set up. It is convenient to divide the setting plates into two main groups respectively dealing with tens of articles at various prices and unit articles at various prices. The arrangement of the setting plates and stop setting rods in the groups in the machine here described is a purely arbitrary one and may be varied as found convenient. The grouping as shown in Figure 5 is as follows:—The four uppermost setting plates K and the top setting plate K' together with their companion setting plates L , L' form one main group a . The four lower setting plates K with the lowermost plate K' and their companion setting plates L , L' , form a second main group b . All the setting plates and stop-setting rods carried thereby and forming the upper group a are employed in dealing with tens of articles at various prices which are apportioned among the rows as follows:—The row a^1 deals with tens of articles at pounds, the row a^2 deals with tens of articles at ten shillings, the row a^3 deals with tens of articles at unit shillings, the row a^4 deals with tens of articles at pence and finally the row a^5 deals with tens of articles at elevenpence. The lower main group b deals with unit articles at various prices apportioned among the several rows as follows:—The row b^1 deals with unit articles at pounds, the row b^2 deals with unit articles at ten shillings, the row b^3 deals with unit articles at unit shillings and the row b^4 deals with unit articles at pence. Finally the row b^5 deals with unit articles at elevenpence. Each row of stop-setting rods M has its inhibiting stop rod N , the rods M^x and M^y carried by the uppermost and lowermost setting plates K' being controlled by the inhibiting

rod which controls the rods in the rows a^4 and b^4 . The uppermost inhibiting stop rod N' controls the whole of the group a of the stop-setting rods M while the lower inhibiting stop rod N' controls the whole of the lower group b of stop-setting rods M .

This arrangement of inhibiting stop rods controlling the rows of stop-setting rods in groups and individually enables the desired 10 selection to be readily effected. When operating for the number of articles a group inhibiting stop is removed by a rod N' according as there are unit articles or tens of articles to be dealt with. When operating 15 for price the stops inhibiting the individual rows are withdrawn by the rods N only those rods N being acted on which correspond to the price rows which are in action.

Figure 14 shows in end view or plan the 20 formation and arrangement of the cams F^2 F^3 on the cam shaft F and the several rotational positions of this shaft and of the cams corresponding to the positions of the ratchet wheel G as determined by the teeth 25 on that wheel. The several radial lines in Figure 14 are marked $G' G^2$ and so on up to G^6 and the positions of these lines indicate the several operative positions of the cams on the stop setting plates K , L , K' and L' , 30 these positions coinciding with the spacing of the teeth around the ratchet wheel G . Thus when the ratchet wheel G and cam shaft F have rotated so that say the tooth G^8 of the wheel is engaged by the stop H the 35 cams will be correspondingly positioned with those as indicated by the line G^8 operative on the setting plates.

The operation of the above described selective mechanism as a whole may now conveniently be detailed. It will be understood 40 that by means of this mechanism, when the keys of the machine are depressed for the purpose of feeding any given sum into the machine as a preliminary to performing an 45 operation thereby, the key-actuated knives E^8 move longitudinally those stop-setting rods M which are presented to them consequent on the selection effected by the cams and setting plates and according to the action 50 of the inhibiting stops dependent on the longitudinal movement imparted to the rods N and N' by the knife B^{8x} . As a result such stops are set up and such product plates released for positioning by these stops that 55 the desired answer can be obtained from the product plates in a manner to be hereinafter described. Further it may be remarked that broadly speaking the process involved in feeding a sum into the machine 60 is as follows:—In the first place one of the two denominational selecting keys A , towards the left hand side of the machine as seen in Figure 1, is depressed, these keys being marked for units and tens of articles. 65 Next those numeral keys corresponding to

the actual number of articles are depressed. The process of depressing the selecting key has rendered the apparatus "alive," but after one or two numeral keys have been depressed the machine ceases to be alive and if other numeral keys are then depressed no action results in the machine. The next step is to depress one of the selecting keys corresponding to the first and highest figure in the price, the numeral keys corresponding to this price figure then being depressed. According to these price figures the next step involves further depression of selecting keys followed by the depression of numeral keys, or the successive depression of numeral keys corresponding to the full price. It is to be noted that the initial depression of a denominational selecting key is necessary to render the machine alive so that the subsequent depression of a numeral key will take effect and when those numeral keys have been depressed in accordance with the value determined by the selecting key the machine once more ceases to be alive.

It is convenient to commence with the procedure and operation when dealing with the number of articles and supposing first that it is desired to perform with the machine an operation involving tens of articles, then the second denominational selecting key from the left hand side of the machine as seen in Figure 1 is depressed. This will cause the end A^2 of that selecting key lever to be moved into the path of the projection E^2 on the differentially actuated plate E . Simultaneously, through the action of the selecting lever on the bar C , the end of the lever C^2 will pull the pawl H clear of the tooth G' of the ratchet wheel G , the pawl H being in engagement with this tooth G' in the normal position of the mechanism when in readiness for performing an operation. The differentially actuated plate E is now free to move under the influence of its spring the small distance permitted until the projection E^2 meets the end A^2 of the selecting lever. The differentially actuated plate E in so moving imparts slight rotation to the cam-shaft F through the rack E^{11} and pinion F' , this rotation being sufficient to bring the pawl H opposite to the inclined back of the tooth G' . The selecting key is now released and as the end of this key lever moves clear of the projection E^2 the differentially actuated plate E is free to move further and at the same time rotate the ratchet wheel G until stopped by the pawl H coming in contact with the tooth G^2 .

The selective mechanism is now alive and the result of rotating the cam-shaft F to the extent indicated has been to bring into operation those cams which act on all the four setting plates K in the group a , so that all these four setting plates are shifted bringing the ends of all the stop rods M

carried by them into the paths of the knives B^o. The cam which acts on the setting plate L' is also operative and this plate is shifted with the end of the group inhibiting rod N' carried thereby. If now any numeral key B for the tens is depressed the knife B^o corresponding thereto is moved towards and strikes the ends of the corresponding stop-setting rods M in the several rows in the group a. Simultaneously the knife B^{ox} strikes the end of the group inhibiting stop rod N' controlling the group a.

As this numeral key is depressed the lever D⁴ is moved, owing to the action of the numeral key lever on the bar D. This movement of the lever D⁴ by the action of the arm D⁵ on the pawl arm J² brings the pawl J into the path of the tooth G' of the ratchet wheel. Simultaneously the arm D⁵ of the lever D⁴ acting on the pawl lever H² lifts the pawl H clear of the tooth G². As a result the ratchet wheel is allowed to revolve slightly until the tooth G' is caught by the pawl J. This extent of rotation of the ratchet wheel and cam-shaft F is not sufficient to affect the action of the cams on the plates set out. The stop rods M and N' therefore remain so that they can be struck by the actuating knives. On release of the numeral key the pawl J is withdrawn out of engagement with the tooth G' by the action of the arm D⁶ and the lever D⁴ on the pawl lever J'. The ratchet wheel and cam shaft F are now free to rotate further until the tooth G³ is engaged by the pawl H which slides down the back of the tooth G² under the influence of the spring H³. This rotational movement of the cam-shaft F has carried those cams which were in action into their inoperative positions so that the setting plates K and L' in the group a are shifted back or to the left to their initial positions under the action of the springs acting on them. Simultaneously those cams have been brought into operation which act on the four setting plates K in the lower group b. The lower setting plate L' is also acted on by its cam so that this plate together with the plates K in the group b are all shifted to the right so that the ends of the rods M and N' carried thereby are moved into the paths of the knives. On depression of the second numeral key corresponding to the unit in the number of articles the corresponding stop rods M are shifted together with the group inhibiting stop rod N' while the pawls J and H are operated as before the one being thrown into the path of the tooth G² and the pawl H moved clear of the tooth G³. On releasing this numeral key the pawl J is lifted clear and the ratchet wheel G and cam-shaft F make a further part revolution until the tooth G⁴ is caught by the pawl H. The cam-shaft has now been rotated sufficiently to take the cams which acted on the

setting plates in the group b out of their operative positions so that those plates which had been set out shift to the left under the influence of their springs and return to their initial positions. It is to be noted that all those rods M the ends of which have been acted on by the knives B^o as also the rods N' acted on by the knives B^{ox} as a result of depressing the numeral keys remain in their altered longitudinal positions when the setting plates K and L' return to their initial positions.

When the cam-shaft is thus rotated to the extent indicated so that the tooth G⁴ is engaged by the pawl H, the mechanism ceases to be alive in that if any numeral keys are now depressed no action can result. The reason of this is that the movement that could be imparted to the pawl lever H² by the lever D⁴ is not sufficient to take the upper or wider part of the pawl H clear of the wider tooth G⁴.

It is now necessary to consider the action of the selective mechanism when a unit number of articles is to be dealt with. It will be understood that all the parts of the mechanism are in their initial positions with the differentially actuated plate E moved to the extreme left of the machine and the cam-shaft F and ratchet wheel G rotated into the position shown in Figures 3 and 4 where the tooth G' is engaged by the pawl H. The first step is to depress the denominational selecting key A on the extreme left of the machine as seen in Figure 1. This throws the end of this selecting key lever A³ into the path of the projection E³ on the differentially actuated plate E. Simultaneously through the action of the selecting key lever A' on the bar C the lever C¹ is moved and its end C² pulls the pawl H clear of the tooth G'. The differentially actuated plate E is thus freed to move to the right until the projection E³ engages the end of the lever A³. The distance which the plate E is thus allowed to move is sufficient to cause rotation of the cam-shaft F until the pawl H is just clear of the tooth G². When the selecting key is released the end of this key lever A³ is taken clear of the projection E³ and the differentially actuated plate can move still further as the pawl H slides down the back of the tooth G² the movement of the plate E and the rotation of the ratchet wheel being checked by engagement of the tooth G³ with the pawl H. The selective mechanism is now alive and the cam-shaft will have been rotated sufficiently to bring into operation those cams which act on the setting plates K forming the lower group b together with the lower setting plate L' carrying the group inhibiting stop rod N'. If now a numeral key B is depressed the corresponding knife B^o together with the knife B^{ox} is moved towards and acts on the

ends of the corresponding stop-setting rods M and inhibiting stop rod N'. Simultaneously owing to the action of the numeral key lever through the bar D the lever D⁴ first pushes the pawl J into the path of the tooth G² which will then be presented to it while the pawl H is withdrawn clear of the tooth G³. This results from the action of the cross-piece D⁵ on the pawl levers J², 10 H². On release of the numeral key the cross-piece D⁶ on the end of the lever D⁴ acts on the lever J' withdrawing the pawl J allowing the tabulating plate E to move and the ratchet wheel G and cam-shaft F to be 15 correspondingly rotated. The pawl H falls on and slides down the back of the tooth G³ into engagement with the tooth G⁴. The cam-shaft has now rotated into a position such that the cams are all inoperative and 20 the setting plates have been returned by their respective springs to their initial positions. The selective mechanism has now ceased to be alive.

It will thus be seen that for dealing with 25 tens of articles the end of the selecting key lever A², co-operates with the selecting stop projection E² and permits rotation and positioning of the cam shaft F with the ratchet wheel tooth G² engaged by the pawl H. For dealing with unit articles the end 30 A³ of the selecting key lever co-operates with the differentially actuated plate projection E³ and permits rotation and positioning 35 of the cam shaft F with the ratchet wheel tooth G³ engaged by the pawl H.

The action of the selective mechanism may now be considered when dealing with the price of the articles. It will be understood that after the cam shaft has rotated 40 as a result of manipulating the selecting and numeral keys for the number of articles until the tooth G⁴ of the ratchet wheel is engaged by the pawl H, the setting plates K, K', L, L', are all in their initial positions 45 at the limit of their travel to the left, that is towards the cam shaft. Owing to the extent to which the differentially actuated plate E has moved to the right in effecting 50 the rotation of the cam shaft there has resulted an alteration in the relative positions of the projections on this plate and the corresponding ends of the selecting key levers. Thus while the ends A⁵, A⁶ and 55 A⁷ of these levers still remain in positions such that they can be moved into engagement respectively with the projections E⁵, E⁶, E⁷, as is apparent in Figure 3, the lever ends A², A³ have moved past the differentially actuated plate projections E², E³ so 60 that if as a result of depressing the corresponding selecting keys the ends of their levers A², A³ are moved they will be respectively opposed to the differentially actuated plate projections E⁵, E⁶.

Assuming first that the price is unit

pounds the denominational selecting key marked for pounds, which is that at the right of the row of selecting keys as seen in Figure 1, is depressed with the result that the end A⁵ of this key lever is thrown into the path of the differentially actuated plate projection E⁵. The action of this selecting key lever on the bar C as before draws the pawl H clear of the tooth G⁴. The plate E now moves and the cam shaft F rotates the extent of this rotary movement being determined by the distance between the end A⁵ of the selecting lever and the projection E⁵. On release of the selecting key the differentially actuated plate E moves further and the ratchet wheel G rotates until the tooth G⁵ engages the pawl H. The apparatus thus again becomes alive and those cams have come into operation which move laterally the setting plates a' and b' in the several groups a and b. The cams acting on the companion setting plates L shift laterally those plates also. Thus the stop-setting mechanism is rendered alive only with respect to the rods M in the row a' which is for tens of articles at unit pounds and in the row b' which is for unit articles at unit pounds. If now any numeral key lever is depressed the knife B⁸ operated thereby will act on the rods presented to it in the rows a' and b'. Simultaneously the knife B⁹ will operate on the corresponding individual stop setting rods N.

It may be noted at this point that if unit articles only are being dealt with the action of the numeral key knife on the stop-setting rods in the row a' will have no effect when the product plates ultimately come to be positioned because the group inhibiting stop rod N' which lies in the row a' will not have been moved when operating the selecting numeral keys for the number of articles.

It is also to be noted that since as already mentioned those stop rods M which have been moved longitudinally by the action of the numeral key knives when operating the machine for the number of articles remain in the longitudinal positions into which they have been pushed, no further action takes place on these rods by the action of the numeral key knives when operating the same keys for the price. Thus supposing that it was desired to perform the sum involved in ascertaining the price of eight articles at £8 each, all the number 8 stops in the units of articles group b would have been pushed by the No. 8 key knife. When, however, the No. 8 numeral key is again operated for the price the knife actuated by this key will move as if to push the No. 8 stop rod M in the row b', which row alone will have been set out into the path of the knife by the setting plate, but as this stop rod has been moved already no further action on it will result. This second operation

of the number 8. numeral key serves the purpose of operating the stop rod N^4 associated with the unit pounds plate P^4 , thus releasing this plate from the stop N^4 . The effect will be to obtain the product of 8^2 namely £64. Similarly if it is supposed that the sum to be performed is twelve articles at £2 each then the action of the numeral keys in dealing with the price will be to push 5 in all the No. 1 stop rods M in the rows a', a^2, a^3 and a^4 and the No. 2 stop rods M in the rows b', b^2, b^3 and b^4 . When operating for price the No. 2 numeral key knife will again tend to push in the No. 2 stop 10 rod in the row b^2 but without effect as this rod has already been pushed in. The desired product will thus be obtained as $(10 \times 2) + 2^2 = 24$.

Turning again to the action of the several 20 denominational selecting keys it will be seen that when the numeral key for pounds is depressed and subsequently released this key acting through the lever D^4 on the pawls B and J permits movement of the differentially 25 actuated plate E and rotation of the ratchet wheel G to the extent of one tooth so that the ratchet wheel is now held by the tooth G^8 engaging with the pawl H . The selective mechanism is then in position for 30 dealing with tens of shillings, those cams being rendered operative which serve to shift the setting plates of the rows a^2 and b^2 . If the price of the articles is a sum for example such as £3.14.0. then the selective mechanism 35 has automatically now passed into the stage when the numeral key for the tens of shillings can be depressed. This will cause the knife of the No. 1 key to act on the corresponding stop rods and by operation of the 40 escapement in the manner previously described will permit the ratchet wheel G and cam shaft F to rotate one step until the tooth G^7 is engaged by the pawl H . When now the numeral key for the units of shillings 45 is depressed and subsequently released the ratchet wheel will rotate one tooth further until the tooth G^8 is engaged by the pawl H .

If the price of the articles is a sum comprising shillings or shillings and pence but no pounds then at the commencement it is necessary to operate the corresponding denominational selecting keys. If the sum amounts to 10s. or more, then the 10s. selecting key is depressed with the result that the end A^8 of this selecting key lever is thrown into the path of the differentially actuated plate projection E^8 . Simultaneously the pawl H is withdrawn from engagement with the tooth G^4 and the differentially actuated plate E is free to move to the extent permitted by the distance between the end of the lever A^8 and the stop E^8 . This is sufficient to cause rotation of the ratchet wheel into the position when on release of the selecting key the tooth G^8 will be en-

gaged by the pawl H which has passed over the tooth G^8 . The cams now brought into operation move the setting plates in the rows a^2 and b^2 . If the sum is less than 10s. then the selecting key for unit shillings is depressed throwing the end of the lever A^7 into the path of the differentially actuated plate projection E^7 . The distance between the end of this lever and this projection is such that withdrawal of the pawl H from engagement 75 with the ratchet wheel tooth G^4 will permit movement of the differentially actuated plate E and consequent rotation of the ratchet wheel G to the extent sufficient to bring the pawl H into engagement with the tooth G^7 the pawl H having missed the teeth G^8 and G^9 .

The operation of the machine if tenpence or elevenpence occurs in the figures in the sum to be dealt with is to some extent determined by the numbering and arrangement of the numeral keys. In the machine more particularly here described this numbering is arranged so as to permit of the machine being used in combination with printing mechanism. As already mentioned the eleven keys are numbered consecutively from 1 to 9 the next key being marked 0 and the last key marked 10. The manipulation of the keys for tenpence or elevenpence is as follows:—For tenpence the key marked 10 is first depressed and then the key marked 0 and for elevenpence the key marked 10 is first depressed and then the key marked 1.

The action of the keys in positioning the cam shaft when pence are to be dealt with may now be considered. In the case of unit pence the selecting key A marked for unit pence is first depressed. Remembering that the pawl H is at that time in engagement with the tooth G^4 of the ratchet wheel and the projection E^3 of the differentially actuated plate E therefore moved beyond the end of the key lever A^3 , it will be seen that depression of this selecting key throws the end of its lever A^3 into the path of the projection E^8 . When therefore the pawl H is lifted clear of the tooth G^4 , the differentially actuated plate E , in its movement up to the point when it is checked by the projection E^8 coming in contact with the end of the lever A^3 , rotates the ratchet wheel G^4 and camshaft until the pawl H is just clear of the tooth G^7 . On release of the selecting key the ratchet wheel can rotate still further until the tooth G^8 is engaged by the pawl H . The rotation of the camshaft up to this point has caused the setting plates K and their companion setting plates L in the rows a^4 and b^4 to be shifted. Operation of the necessary numeral key acts through its key knife on the corresponding setting rods M in a manner already described. At the same time owing to the operation by this numeral key of the escapement, the pawl H is lifted 100 105 110 115 120 125 130

over the tooth G^8 and on release of the numeral key the camshaft F rotates until the tooth G^9 is engaged by the pawl H. The procedure of feeding the sum into the machine is then completed.

- If now the price to be dealt with is ten pence the denominational selecting key A marked for tens of pence is depressed. This throws the end of this selecting key lever 10 A^2 into the path of the projection E^9 on the differentially actuated plate E. Since the distance between the end of the lever A^2 and the projection E^9 is the same as the distance between the end of the selecting key 15 lever A^3 and the projection E^8 , it will be apparent that the actual effect of depressing the tens of pence selecting key is primarily the same as when depressing the units of pence selecting key. Thus by depressing this key the differentially actuated 20 plate E moves until the projection E^9 meets the end of the lever A^2 when the ratchet wheel has been rotated until the pawl H is just clear of the tooth G^7 . The release of 25 the selecting key allows the camshaft F to rotate until checked by the pawl H engaging the tooth G^8 . The same cams are again operative as when dealing with unit pence and the setting plates K and L in the rows 30 a^4 and b^4 are shifted since it will be remembered that these rows comprise ten stop setting rods M. The numeral key marked 10 is now depressed and its knife acts on the No. 10 stop setting rods M. The escapement actuated as before by the numeral key 35 allows rotation of the camshaft until the pawl H is in engagement with the tooth G^9 . If, as may be the case with the present construction, the machine is combined with 40 other mechanism for printing the figures of the sum as fed in, the numeral key marked 0 is now depressed, but inasmuch as this key is provided with no key knife B⁹ its depression has no effect on the stop setting 45 rods but merely operates the escapement. The cam shaft however can rotate no further as the differentially actuated plate E has reached the limit of its travel.
- Where the price is elevenpence the procedure commences as in the case of ten pence with depression of the tenpence selecting key so that the end of that key lever A^2 engages the differentially actuated plate projection E^9 . When this key is released 50 the tooth G^8 is engaged by the pawl H. The number 10 numeral is then depressed and released causing operation of the escapement so as to move the pawl H out of engagement with the tooth G^8 and allow the ratchet wheel to rotate until the tooth G^9 is engaged by the pawl H. In this position those cams are operative which shift the setting plates K'. The No. 1 numeral key is 55 now depressed which acts through its knife B^9 on the setting rods M'.

It will be convenient to note the procedure and action of the mechanism when dealing with such price sums as £3.0.7. 10s. 5d. and 8s. 3d. or 8s. 11d.

Taking first of all a sum of £3.0.7d. First 70 the denominational selecting key for pounds is operated which permits rotation of the ratchet wheel until the tooth G^5 is engaged by the pawl H. The No. 3 numeral key is now depressed and released and operates 75 the escapement in the manner already described so as to allow the ratchet wheel to rotate until the tooth G^6 is engaged by the pawl H. The selecting key for unit pence is now operated which first throws the end 80 of this lever A^3 into the path of the differentially actuated plate projection E^8 and allows the camshaft and ratchet wheel to rotate until on the release of the selecting key the tooth G^8 is engaged by the pawl H. 85 The cams actuating the setting plates in the rows a^4 and b^4 are now operative and the numeral key No. 7 is depressed, the action being as already described.

In the case of a sum such as 10s. 5d. the first step is to depress and release the 10s. selecting key which in the manner already described permits rotation of the cam shaft until the tooth G^9 is engaged by the pawl H. The No. 1 numeral key is now depressed 90 and on its release results in the camshaft being rotated one step until the tooth G^7 is engaged by the pawl H. The numeral key marked 0 is now depressed, which as already mentioned only operates the escapement, with a result that the cam shaft rotates one step further until the tooth G^8 is engaged by the pawl H. The camshaft is now in position for operation of the No. 5 numeral key for unit pence. As an alternative to operating the key numbered 0 which is convenient when the machine is combined with means for printing the figures, the selecting key for unit pence may be operated after depressing the numeral key 95 for tens of shillings. As will be understood this will have the effect of operating the escapement so as to permit the camshaft to rotate into the necessary position for unit pence when the tooth G^8 is engaged by the 100 pawl H.

In the case of a sum such as 8s. 3d. the selecting key for unit shillings is first depressed and released and its action as already described results in rotating the camshaft into the necessary position for units of shillings when the tooth G^7 is engaged by the pawl H. The No. 8 key is then depressed and on its release the escapement 110 permits the camshaft to rotate until the tooth G^8 is engaged by the pawl H. The No. 3 numeral key is now operated. If the sum were 8s. 11d. the procedure, after the No. 8 numeral key has been operated for 115 the shillings, would be the same as already 120 described.

described when dealing with elevenpence, that is to say first of all the numeral key marked ten would be operated and then the numeral key marked 1.

5 The construction and operation of the product plates and the manner in which they are positioned may now be described.

Referring to Figure 6 it will be seen that at a suitable point in its length each stop setting rod M is notched or cut away as at M'. From this lower portion M' leads an incline M² to a higher part of the rod. One end of a positioning stop O rests on the stepped end M' of the setting rod. The other end of this stop O lies in a hole O' in a fixed plate O² carried by the framing of the machine. The holes O¹ are arranged in single rows and each row of stops corresponds to a row of stop setting rods M in the selective mechanism shown in Figure 5. A spring O³ coiled around each stop O is connected at one end to the stop and at the other bears against the face of the plate O². The arrangement is such that longitudinal

25 movement of the stop setting rod M causes the end of the stop O to ride up the incline M² with a result that the other end of the stop O projects from or is set up on the face of the plate O². When the stop setting rod M is returned to its initial position that is to say pushed back towards the front of the machine the stop is withdrawn by the action of a spring O³ this resetting process being brought about by mechanism to be hereinafter described.

There are a series of plates O² which are divided into two groups according to the grouping indicated with reference to the selective mechanism shown in Figure 5.

40 One of these groups of plates O² which in the present machine is that designated a for dealing with the products of tens of articles at varying prices is disposed in the upper part of the machine. The plates

45 forming the second group designated b are disposed in the under part of the machine. Adjacent and parallel to each plate O² is a product plate P which carries on that face which is opposed to the plate O² V-shaped

50 guides P'. Each product plate P can move parallel to itself into a position which will be determined by the guides P' coming in contact with one or more stops O set up in the corresponding row. This construction

55 and manner of positioning the product plates is as described in the specification of U. S. A. Letters Patent No. 1,088,207 previously referred to. The a group of

60 product plates P is seen at the top of the machine as viewed in Figure 8 these plates being respectively marked Pa¹, Pa², Pa³, Pa⁴, corresponding to the rows of plate setting rods M in the group a shown in Figure 5. Thus the product plate Pa¹ deals with

65 tens of articles at pounds, the plate Pa²

deals with the products of tens of articles at 10s. the plate Pa³ deals with tens of articles at unit shillings and the plate Pa⁴ deals with tens of articles at pence. The b group of product plates is disposed towards the underside of the machine these plates corresponding to the rows of setting rods M in the b group shown in Figure 5. The several rows of stops O are to be seen in Figure 8 in their relationship to each other and to the product plates the positions of which they determine. The rows of stop setting rods M are superimposed and extend from front to back of the machine to varying extents according to the positions of the rows of stops O. As will be seen in Figure 8 the rows of stops O lie one behind the other from front to back of the machine and the upwardly directed stops in the rear-most of these rows Oa is seen in Figure 10 which represents an elevation of the back of the machine. This figure also shows the downwardly directed stops Ob of the rear-most row in the lower or b group.

It will be noted that for positioning the product plate Pa⁴ dealing with tens of articles at pence there are provided eleven stops O corresponding to the elevenpence that have to be dealt with. The No. 11

stop at the extreme right hand side of this row is set up by the stop rod M^x in the row a⁵ as seen in Figure 5. This rod M^x is that situated towards the left hand end of the setting plate K' and behind the frame F⁶

F⁷ carrying the stop setting rods the rod M^x is connected across the rods M in the row beneath to the other rod M^y carried at the opposite end of the setting plate K'. The end of the rod M^y seen in Figure 5 and carried by the plate K' is only for

guiding purposes the other end of this rod, however, being cut away as at M' (Figure 6) so as to operate on its stop rod O. The setting rod M^x the end of which is actually

110 acted on by a key knife B⁹ when set out into the path of this knife does not extend backwards beyond the point where it is connected across to the rod M^y. Thus though the stop setting rod M^x is situated towards

115 the left hand end of the rows of rods M it is actually operative by its longitudinal movement to set up a stop O at the right hand end and this stop forms the eleventh in the row of ten stops set up by the rods M in the row a⁴.

120 It will be convenient to note here the result of setting up the stops and positioning the product plates when dealing with sums involving tenpence and elevenpence. In the case of tenpence the number 10 stop is

125 set up as a result of depressing the numeral key marked 10 and the product plate is positioned accordingly by the V guides coming in contact in a known manner with

130 this No. 10 stop and such other stop, if

any, which may be set up according to the number of articles to be dealt with in the sum. In the case of elevenpence, however, as already described the No. 10 numeral key is first operated, thereby setting up the No. 10 stop, and then the No. 1 numeral key is operated, which, however, owing to the setting plates K' having been shifted by cam action results in 10 setting up the No. 11 stop through the action of the No. 1 key knife on the stop setting rods M' . The number 11 stop being beyond the No. 10 stop prevents the No. 10 stop from being operative on the V-guides 15 in positioning the product plate even when the number of articles dealt with is 11 since in the case of eleven articles at 11d. the stops set up will be as follows:—In the row of stops controlled by the setting rods M in the 20 row designated a' , dealing with tens of articles, there will be set up the stops Nos. 10 and 11, while in the row designated b' , for dealing with unit articles, there will be set up the stops Nos. 1 and 11 so that the 25 necessary product will be ascertained in the form $(10 \times 11) + (1 \times 11)$.

Each product plate P carries groups of product pins P^2 which are inserted and fixed in holes formed in the product plates P . 30 The grouping of these pins in the upper plates P is to be seen in Figure 8 and the length of each pin represents a product determinable when a product plate is positioned. One series of these pins P^2 as they 35 project from the underside of a product plate P is to be seen in side elevation in Figure 12. The grouping of these pins is in accordance with the products which it is possible to obtain from the positioning of 40 any one plate, thus for example the plate $P_{a'}$ for dealing with tens of articles at unit pounds is provided with two groups of product pins for dealing respectively with tens of pounds and hundreds of pounds. 45 On the other hand the plate $P_{a'}$ for dealing with tens of articles at pence has four groups of product pins P^2 which deal respectively with unit pounds, tens of shillings, unit shillings and pence. This splitting of 50 the products and the employment of pins whose length is a measure of the value of a product, is in accordance with the construction embodied in the specification of the U. S. A. Letters Patent No. 1,088,207 55 already referred to.

The parallel movement of the product plates into the positions determined by the stops set up is effected in the following way. Over the a group of product plates as seen 60 in Figures 8, 16 and 16^a there lie a series of flat bars P^3 which can slide from front to back of the machine. Each bar carries a cross-piece P^4 with downwardly directed ends P^5 which lie against the forward edge 65 of a product plate P . Connected to a stud

on each bar P^3 is one end of a coiled spring P^6 which runs to the rear of the machine where its other end is attached to one arm of a two-armed lever Q, Q' , pivoted on a vertical axis Q^2 . When the mechanism is 70 operated which causes the parts of the calculating machine to perform their several functions the lever Q, Q' is moved and a pull is then exerted through the springs P^6 on the sliding bars P^3 , this pull being communicated through the cross-pieces P^4, P^5 to the product plates P . Those product plates which have been released by the withdrawal in the manner hereinafter to be described, of the inhibiting stops, then move towards the 80 rear into positions parallel to themselves until checked by the stops O , which have been set up, coming in contact with the V guides P' . Since the projections P^5 on the ends of the cross-pieces P^4 always move 85 parallel the necessary parallelism of the product plates when positioned is ensured.

Turning now to the inhibiting stops and their operation it will be seen from Figure 7 that in each rod N , which controls an individual inhibiting stop, there is cut a notch N^2 with an incline N^3 leading down to it. On the upper part of the rod N adjacent to the incline N^3 rests the lower end of a stop pin N^4 whose upper end projects through a hole in the fixed plate O^2 . A spring N^5 coiled round the stop N^4 is attached thereto at one end and at the other end bears on the underside of the plate O^2 thus tending to force the stop N^4 downwards. When the rod N is moved longitudinally by the action of a key knife B^{9x} the lower end of the stop N^4 moves down the incline N^3 into the recess N^2 with the result that the upper end of the stop N^4 is withdrawn into the hole in the plate O^2 . This hole in which the stop N^4 lies is conveniently in line with but slightly spaced apart from the row of holes in the plate O^2 in which lie the positioning stops O , see 100 Figure 8. The end of the stop N^4 when in its operative position that is to say when raised and projecting from the face of the plate O^2 engages a recess or notch P^{10} in one of the V-guides P' of the corresponding product plate P as clearly shown in Figure 8. Until this individual inhibiting stop N^4 has been withdrawn by imparting longitudinal movement to the rod N the product plate controlled thereby cannot move. 110

The inhibiting stops which control respectively the a and b groups of product plates are arranged and operate as follows:—The end of the setting rod N' which controls one of these stops has formed in it a recess N^2 with an incline N^3 leading to it like the rod N . The group inhibiting stop pin N^6 is disposed with one end resting on the rod N' adjacent to the incline N^3 . The other end of this stop passes through a hole in a fixed plate O^4 conveniently disposed towards the 120

front of the machine. Over this plate lies a flat bar P^7 which can slide from front to back of the machine parallel to the adjacent sliding bars P^3 . On the side of this bar P^7 which faces the fixed plate O^4 is a projection P^8 so arranged that it can be engaged by the projecting end of the stop N^6 in such a way as to prevent the plate P^7 from moving towards the rear of the machine. The plate P^7 extends from front to back of the machine over the product plates P and carries on its underside studs P^9 each of which is so positioned that it lies against the rear edge of a product plate. These studs P^9 and their positions with regard to the product plates are clearly seen in Figure 8. Each plate P^7 controls a group of product plates, that plate which is shown in Figures 7 and 8 being the one which lies in the upper part of the machine and controls the a group of product plates.

It will be seen that so long as the end of the stop N^6 engages the projection P^8 the plate P^7 cannot move and in turn it holds immovable all the product plates in the a group. When the setting rod N' is moved longitudinally by the action of the knife B^9 the stop N^6 drops into the recess N^2 and its end is withdrawn from engagement with the projection P^8 . The bar P^7 and the a group of product plates are all now free to move under the influence of the springs P^6 when the lever Q is moved. The product plates then assume the positions determined by the stops O that have been set up. A projection Q^3 on the lever Q lies against the rear end of the bar P^7 and thus as the lever Q moves away the bar P^7 is left free to slide towards the rear of the machine as the product plates take up their positions, this movement being imparted to the bar P^7 from the product plates through the studs P^9 . On the return movement of the lever Q , the projection Q^3 presses against the end of the bar P^7 and forces it back towards the front of the machine into its initial position. In so moving the bar P^7 carries with it the product plates to which in this case movement is imparted through the studs P^9 . When the return movement of the bar P^7 is completed it is locked once more by the stop N^6 , as hereinafter described.

The b group of product plates P as already mentioned are disposed on the underside of the machine with their groups of product pins P^2 upwardly directed and the movement of these product plates is effected by sliding bars P^3 similar to those which control the movements of the upper or a group. Individual and group inhibiting stops N^4 and N^6 are also provided, the whole group of product plates being controlled by a sliding bar P^7 . A second lever Q Q' is provided as shown in Figure 10 to which is connected the ends of springs P^6 whose other

ends are connected to sliding bars P^3 . The two levers Q Q' are connected by a cross-piece Q^4 as shown in Figure 10. The lower group of product plates therefore and their controls together with the rows of stops which determine the positioning of these plates and the setting rods which actuate these stops are really a duplication of the upper product plates and their controlling and setting mechanism. Obviously however, the groups of product pins P^2 in the lower product plates differ from those pins carried by the upper plates in that the products dealt with by the lower group relate only to unit articles at varying prices.

When the product plates are returned to their initial positions it is clearly necessary also to return all the stop setting rods whether they control the positioning stops or the inhibiting stops and this return is effected by pushing back towards the front of the machine all those rods which have been moved longitudinally by the actions of the key-operated knives. The return of these rods is effected by a member which is applied to the rear ends of the rods and pushes them towards the front of the machine. This member is shown in plan in Figures 11 and 15 and in rear elevation in Figure 26. It is also shown in part in Figures 16 and 16^a. These figures show the ends of a set of stop setting rods M with the companion inhibiting stop rod N and the positioning and inhibiting stops O and N^4 in section in a plate O^{2x} which serves as a guide for the ends of the stops O and N^4 which are adjacent to the setting rods M and N . The ends of the rods M and N pass through slots in the vertical part of the bar O^{2x} , this bar being fixed to ribs Z of the framework of the machine by means of block O^8 disposed beneath it. Two parallel members O^{4x} are so arranged in suitable guides formed by the vertical ribs Z that they can slide in either direction from front to back of the machine. Carried by and between these members O^{4x} is a series of plates O^5 each disposed opposite to the rear ends of a row of stop setting rods, the latter terminating at different distances in a front to back direction with relation to the machine and conveniently at points slightly to the rear of the row of stops O which they respectively control. Figure 11 shows the rear ends of two rows of stop setting rods M and N with their rows of stops O and N^4 . One of these rows of stops is upwardly directed, the stop rods being shown in section, while the other row is downwardly directed. These are the stops Oa and Ob which are seen in Figure 10. The rearmost plate O^5 is provided with a laterally projecting arm O^6 . On the spindle Q^2 which constitutes the axis about which the double lever Q Q' rotates is mounted a lever with

two arms Q^5 , Q^6 (Figure 10), the arm Q^5 is directed towards and overlaps in a separate plane the end of the arm Q^6 . Towards the end of the lever Q^5 is mounted a spring-controlled snap-over pawl or detent Q^7 so arranged with relation to the end of the arm Q^6 that as the lever Q^5 moves in one direction that is to say towards the back of the machine the detent Q^7 will snap over the end of the arm Q^6 without having effect thereon. On the other hand as the lever Q^5 moves back again that is to say towards the front of the machine the detent Q^7 will engage the arm Q^6 and push this arm and with it the plates O^5 towards the front of the machine. These plates O^5 acting on the ends of the stop setting rods will push all of them towards the front of the machine and thus restore them to their initial positions. The plates O^5 then move towards the rear of the machine under the action of a spring not shown in the drawings. The manner in which the lever Q^5 , Q^6 is moved will be described hereafter.

25 Pins O^7 are provided on the plates O^2 which engage with the outer edges of the V-shaped guides P' when the product plates are moved back so as to insure that these plates will take up their correct positions.

30 When the product plates P have been positioned by the stops set up it is necessary to ascertain and add together the several products so as to obtain the required answer to the sum being performed. The mechanism employed for thus adding together the products is in its general features, as already mentioned, that described in the specification of United States of America Letters Patent No. 1,075,003. It

35 will be seen in Figure 8 that the product pins P^2 are so disposed on their plates that the several sets lie in groups running from the front to the back of the machine. The product pins carried by the lower or b group of plates are similarly arranged so that there is comprised in each group all those product pins carried by the several product plates which relate to what may be termed a similar class of products. Thus

40 taking the groups from the right to the left hand side of the machine as viewed in Figure 8, that group at the extreme right hand end comprises products of units and tens of articles at pence. The second group comprises products of units and tens of articles at unit shillings. The third group units and tens of articles at tens of shillings. The fourth group units and tens of articles at unit pounds. The fifth group units and tens of articles at tens of pounds and finally the last group which is at the extreme left hand end comprises units and tens of articles at hundreds of pounds. All the products in each group are collected and added in one

45 unit of the adding mechanism. These add-

ing units are shown in Figs. 12, 17, 18, 19, 20 and 26, but for the sake of simplicity with only one of the feeling devices which forms part of it. This adding device comprises a series of pulley wheels R over all of which runs a flexible tape or wire S . One end of this tape is connected to the periphery of a pulley R' which can be rotated and fixed by some suitable device so as to adjust the tension and length of the tape S . The device may conveniently consist of a screw thread S^7 which can be rotated by hand by means of a milled head S^8 . The other end of the tape is connected to a template disc S' rotatably mounted on a spindle S^2 with a coiled spring S^3 so connected to the template and the fixed spindle that tension is exerted on the tape S . Thus if one or other of the pulleys R is moved either up or down according to the position of that pulley the tape S will be taken up or let out in certain increments and the template S' will correspondingly rotate. Each pulley R is carried by a frame R^2 mounted in a groove R^{10} in one of the partitions R^{11} which tends from front to rear of the machine and separates the various adding units. Each frame R^2 is held in its groove R^{10} by means of the overlapping heads of screw R^{12} in the partitions R^{11} in such a manner that it is free to slide vertically therein. The pulley R is conveniently mounted at one end of this frame and at the other end is a pin or finger R^3 . On each frame R^2 is carried a rack R^4 , which is conveniently formed by a row of pins or studs, and engaging with this rack is a toothed pinion T on one side of which is a short sleeve provided with a lateral axially directed projection T' . The pinions T are loosely mounted on a shaft T^2 which carries several pins or studs T^3 each positioned so as to abut against the projection T' of a pinion T . Each frame R^2 is so disposed beneath or above a product plate P and in relation to a group of product pins P^2 carried thereby that when the product plate is positioned by the stops that have been set up the corresponding product pin P^2 will be presented opposite to the end of the finger R^3 . If the frame R^2 is now released so that the finger R^3 can come in contact with the end of the product pin presented to it the length of this pin will be felt by the finger R^3 . Thus the frame R^2 and consequently the pulley wheel R carried thereby will have moved an amount determined by the length of the product pin P^2 and therefore the tape S will have been released or let out an amount which is a measure of the product in question.

50 The template S' is notched or stepped to varying depths as at S^4 in a known manner these steps corresponding to the several product increments. Adjacent to the tem-

plate is pivoted at U a two-armed lever of which one arm U' terminates in a feeler or finger while the other arm U² carries a quadrant U³ on the face of which is marked 5 numbers corresponding to the increments of the steps S⁴, these members being visible through openings U⁴ in a fixed plate U⁵. Since each pulley R is carried by a frame R² provided with a finger R³ when the several product plates have been positioned and all the frames R² are simultaneously released the several products are felt with the result that the pulley wheels move respectively to the extents permitted by the 10 dimensions of the product pins and the tape S is let out and the template S' takes it up and rotates an amount which is a measure of the sum of all these products. This sum is ascertained from the template S' by the 15 feeler arm U' which conveniently is not allowed to operate until the template S' has rotated into the position determined by the sum of the products of that unit group. As the arm U' engages the template notch the 20 indicating quadrant U³ will move into a position such that the corresponding number will be presented at a suitably disposed window.

The shaft T² is carried in suitably disposed bearings T⁴ and on one end, preferably its rear end, is keyed a pinion T⁵ which gears with a rack carried by a sliding bar T⁶. In Figure 10 will be seen the rack bar T⁶ with the several pinions T⁵ which belong to the adding units. The bar T⁶ is suitably guided so that it can move across the machine, movement being imparted to it by a link T⁷ connected at one end to the rack bar at T⁶ and at the other end to a crank arm T⁸ mounted on a shaft T¹⁰. At first the rack bar T⁶ is in its limit position towards the right of the machine, that is to say towards the left in the rear elevation of the machine shown in Figure 10. Each 25 shaft T² has now been rotated into such a position that by reason of the stops or studs T³ bearing against the pinion projections T⁵ each pinion has been rotated so that it has moved its rack R⁴, frame R² and pulley R into their extreme or zero positions. At a suitable stage when the machine is being put through its cycle of operations and after the product plates have been positioned by the stops set up, the rack bar T⁶ is moved across the machine to its other limit position that is to say towards the right as viewed in Figure 10. This movement of the rack bar has rotated each shaft T² so that the studs T³ move away from the 30 pinion projections T⁵. As a result of the tension on the tape S exerted by the spring S³ each pulley wheel R and frame R² now moves to the extent permitted by the length of the product pin P² which is presented to and felt by the finger R³. As the rack

R⁴ moves it rotates the pinion T but can never do so to such an extent that the rotation of the pinion and consequently the movement of the frame R² is checked by the stud T³ on the shaft T².

When the template S' has assumed the position corresponding to the sum of the products felt by the fingers R³ this product sum is felt by the lever U' and indicated on the quadrant U³ at the end of the first half of the cycle of operations performed by the machine. When the answer to the sum performed by the machine has been read off all the levers U² are returned to their initial positions by a bar operated in a manner to be hereinafter described and when clear of the templates the rack bar T⁶ is moved back again. This causes rotation of all the shafts T² when the studs T³ on each shaft pick up the several pinions T in the positions which they have assumed and rotate them thus setting back to their zero positions all the frames R² and pulley wheels R. The template S' consequently is reset at zero.

The mechanism by which a carry is effected from one adding unit to another may now be described. One of the pulleys over which the tape S passes and preferably that pulley designated R^x in Figure 12 which is nearest to the template S' is mounted on a slide R^{2x} in the same way as each other pulley but this slide has no feeling finger for ascertaining the length of a product pin. Further, this slide is movable in two directions so that the pulley R^x can be moved either inwards and towards the other pulleys or outwards. Consequently by suitable movement of the slide R^{2x} which carries this pulley the tape S can not only be let out but also taken up. The slide is pivotally connected at R⁵ to a lever R⁶ pivoted at R⁷ and having its free end R⁸ cranked or bent over to one side and downwardly directed towards the template S' of the adding unit of next lowest denomination.

Mounted on the end of the shaft T² opposite to that which carries the pinion T⁵ is a disc T¹¹ the periphery of which lies near the face of the slide R^{2x}. Projecting from this slide is a pin R⁹ the end of which lies close against the periphery of the disc T¹¹. At a suitable point in the periphery of this disc is formed a notch. As long as the smooth periphery of the disc is presented to the projection R⁹ the slide R^{2x} is locked and cannot drop so as to let out the tape S but when the shaft T² has been rotated sufficiently to present the notch in the disc T¹¹ to the projection R⁹ then the slide R^{2x} will be free to move to the extent permitted by the carry lever R⁶ R⁸ and in accordance with the carry that is to be effected. On one face of each template S' 130

is disposed two or more quadrant lateral projections S^5 over which lies the end R^8 of the carry lever. These projections are arranged at different radial distances from the centre of the template. When the notch in the disc T^{11} has permitted movement of the slide R^{2x} the end of the carry lever R^8 will fall on to the quadrant projection S^5 which is beneath it. If the template has not been rotated sufficiently to effect a carry then the amount of movement permitted to the pulley R^x in the unit of next highest denomination is not sufficient to let out the tape S enough to rotate the template S' of that unit an amount equal to a further integer. If, however, a single carry is required the carry lever drops on to the next projection S^5 and permits such movement of the pulley R^x as will cause the template S' in that unit to rotate to the extent of one integer. If there is more than one carry to be effected the carry lever drops on to the next template projection and permits yet further movement of the pulley R^x . As will thus be understood the movement if any which is allowed to the pulley R^x through the movement of the carry lever R^6 R^8 is determined by the positioning of the template S' in the adding unit of next lowest denomination.

The notch in the disc T^{11} is so formed that as this disc is rotated with the shaft T^2 for the purpose of resetting the frames R^2 and pulleys R , the slide R^{2x} together with the pulley R^x will be lifted up and returned to their initial positions and there locked by means of the projection R^9 . The notches in the several discs T^{11} are so positioned that they will be presented to the slide projections R^9 successively and will pick up these projections and return the slides in succession as all the shafts T^2 are simultaneously rotated by the rack bar T^6 in the manner already described.

45 The operating mechanism may now conveniently be considered this mechanism being shown in Figs. 9, 21, 22, 23 and 24.

The mechanism is actuated by a lever V provided at one end with a handle and at the other keyed on a shaft V' . Mounted on the shaft V' and thus connected to and operative with the lever V is a plate V^2 which carries certain sectors or cams V^3 , V^4 and V^5 and laterally projecting pins V^6 and V^7 . Taking these successively and their respective functions, V^3 is curved on its lateral face remote from that presented to view in Figure 9. This face is opposed to the right hand end of the differentially actuated plate E and so shaped that when the lever V is rocked or pulled towards the front of the machine, that is to say to the left as viewed in Figure 9, this cam will bear against the end of the differentially actuated plate E and push it back to its zero position. Simulta-

taneously of course this movement of the differentially actuated plate E rotates back against the cam-shaft F until the pawl H is once more in engagement with the tooth G' of the ratchet wheel G .

A lever W pivoted at W' carries at one side of it a roller W^2 so positioned that it can strike the end of the cam sector V^4 and mount it. An extension W^3 of the lever W is pivotally connected to one end of a link Q^8 the other end of which is pivoted to the cross piece Q^4 connecting the double levers Q , Q' mounted at the rear of the machine. The lever W is also provided with an arm which is curved and shaped as at W^4 and positioned so that it can be engaged by the pin V^6 . The end W^5 of the lever rests on the pin V^6 and is locked thereby when the parts are in the positions shown in Figure 9. As the lever V is pulled towards the front of the machine the pin V^6 is moved clear of the end W^5 of the lever W which is then free to fall. The end of the sector V^4 then strikes the roller W and causes the whole lever W to turn about its pivot until the roller W^2 mounts on to the outer face of the sector V^4 when the lever W is locked in the position which it then occupies. In the course of its movement the lever W imparts a pull on the link Q^8 and moves the levers Q , Q' this movement releases and brings about the sliding movement of the bars P^3 and P^7 shown in Figure 8 and previously described in connection therewith. On the return movement of the lever V the roller W^2 remains on the sector V^4 until it reaches and drops off the end of this sector. The pin V^6 then strikes the curved surface W^4 and carries the lever W back again until the end W^5 of this lever again rests on and is locked by the pin V^6 .

A two-armed lever X , X' is pivoted at X^2 and carries at the end of the arm X a roller X^3 which moves on the upper face of the sector V^5 . The end of the lever arm X' is slotted and engages a pin X^4 carried by one of a pair of levers X^5 mounted concentrically at X^6 . These levers X^5 carry a bar X^7 which runs across the front of the machine adjacent to the indicator sector levers U^2 . As the lever V is pulled towards the front of the machine the roller X^3 remains on the sector V^5 until the end of this sector is reached when the roller drops off the end of this sector and the lever is free to turn and move the bar X^7 clear of the indicator sector levers U^2 all of which can then drop into the positions determined by their feeler arms engaging the positioned templates S . On the return movement of the lever V the roller X^3 mounts on to the sector V^5 and all the indicator sectors U^3 are moved back to their zero positions by the bar X^7 .

The movement of the lever Q^5 , Q^6 by means of which the resetting of the stop-setting rods is effected is brought about

through the movement which is imparted by means of the lever W and link Q^8 to the double lever Q' . These two levers Q' are keyed on the rocking shaft Q^2 which as shown in Figure 10 carries fixed on it two collars Q^9 between which is disposed a boss Q^{10} with which the levers Q^5 Q^6 are integral. This boss is loosely mounted on the shaft Q^2 and carries a pin Q^{13} which projects vertically into a quadrantal recess in one of the collars Q^9 as shown in Fig. 15. Thus as will be understood the shaft Q^2 can rotate to a certain extent without imparting rotation to the boss Q^{10} and the levers carried thereby. The movement beyond this extent, which is determined by the dimensions of the recess in the collar Q^9 , brings the pin Q^{13} on the boss Q^{10} against the side of the recess and causes rotational movement of the boss Q^{10} and the levers Q^5 and Q^6 move with it. The position of the pin Q^{13} in the recess is such that as the levers Q' are moved, consequent on the pull exerted through the link Q^8 by the lever W , the shaft Q^2 will rock but will not move the boss Q^{10} and levers Q^5 and Q^6 until the lever W is near the end of its movement towards the front of the machine. Such movement will then be given to the levers Q^5 Q^6 as will cause the detent Q' to snap over the end of the arm O^6 . The lever Q^5 will now remain in the position which it then occupies while the lever W performs the greater part of its return movement. As the shaft Q^2 rocks back again at a point towards the limit of its movement, it will again pick up the boss Q^{10} and so move the lever Q^5 back, this is to say towards the front part of the machine. As the detent Q' now engages the end of the arm O^6 a push will be exerted thereon resulting in the resetting of the stop-setting rods. In this resetting movement the lever Q^5 will so move relatively to the end of the arm O^6 as the latter is pushed that when the resetting plates O^5 have accomplished their functions the detent Q' will slide off the end of the arm O^6 . That arm and the resetting plates O^5 are now free to move once more towards the rear of the machine and clear of the ends of the stop setting rods owing to the action of the spring or springs O^8 controlling the resetting plates O^5 (Fig. 16^a).

It will be seen that the lever Q^6 has connected to it one end of a rod Q^{11} , whose other end extends forwardly and terminates at Q^{12} in such a position that when the operating lever V is in its normal or initial position, as shown in Figure 9, the rear corner of the quadrant V^5 will strike the end Q^{12} of the rod Q^{11} and lock the levers Q^5 Q^6 in their zero positions.

A two-armed lever Y Y' is pivoted at Y' and carries towards the end of the arm Y' a roller Y^3 which runs on the upper surface

of the sector V^5 . The other arm Y is connected by a link Y^4 to a crank arm T^1 mounted on the end of the shaft T^{10} remote from the crank arm T^9 . As the lever V is pulled towards the front of the machine the roller Y^3 runs on the surface of the sector V^5 until the end of this sector is reached when it drops. Immediately afterwards the pin V^7 which projects laterally from an extension of the sector V^5 strikes a projecting part Y^5 of the lever arm Y' and causes the lever Y Y' to turn about its pivot. As it so turns motion is imparted through the link Y^4 to the crank shaft T^{10} with the result that the rack bar T^6 is moved across the machine thus releasing in the manner already described the pulleys R and the fingers which feel the product pins. On the return movement of the lever V the roller Y^3 mounts the sector V^5 and the lever Y Y' is turned back again thus imparting reverse rotation to the shaft T^{10} which slides back the rack bar T^6 to its initial position with the result that the pulleys R and product feelers are reset to zero as described.

A short crank arm V^9 mounted on the shaft V' is connected to a dashpot V^8 which prevents the motion of the lever V being too rapid. This dashpot is not always essential but is convenient when the mechanism is hand-operated. As will be apparent if necessary the lever V may be operated from a shaft which rotates in a constant direction this shaft being provided with a crank and rod connecting it to the lever V . Such a shaft may be rotated by power through suitably controlled clutch mechanism in some convenient manner, as for example is described in the present applicant's current application for United States Letters Patent Serial No. 343,630, filed December 9, 1919.

It is to be understood that the above described calculator may be modified in details of construction and used in various ways. By suitable modification of the parts it can be adapted for use with different monetary systems or for performing calculations involving different weights or measures. The calculator may also be combined with other mechanisms with which it will cooperate. The scope of the apparatus also may be varied to meet requirements.

What I claim as the invention of EDWARD RUSSELL CLARKE deceased and desire to secure by Letters Patent is:

1. In a calculating machine the combination of a plurality of members each separately movable parallel to itself in two directions at right angles, a plurality of stops which when set up determine the positions into which these members move, a series of longitudinally movable rods by means of which the determining stops are set up, the ends of these rods being all grouped like

a chess board in rows parallel in two directions and in one plane, a series of knives each adapted to reciprocate towards and between the grouped ends of the stop setting rods, keys by means of which these knives are actuated, and key controlled means for shifting the ends of the stop setting rods in rows at right angles to the knives so as to bring the ends of the rods into the paths of the knives as set forth.

2. In a calculating machine the combination of a plurality of members each separately movable parallel to itself in two directions at right angles, a plurality of stops which when set up determine the positions into which these members move, a series of longitudinally movable rods by means of which the determining stops are set up, the ends of these rods being all grouped like a chess board in rows parallel in two directions and in one plane, a series of stops which until withdrawn respectively serve to inhibit in groups and individually the positioning of the parallel movable members, a series of longitudinally movable rods by means of which the inhibiting stops can be withdrawn these rods being disposed and grouped with the stop setting rods, a series of knives each adapted to reciprocate towards and between the grouped ends of all these rods, keys by means of which these knives are actuated, and means controlled from the keys for shifting the ends of the rods at right angles to the knives so as to bring the ends of the rods into the paths of the knives as set forth.

3. In a calculating machine the combination of a plurality of members each separately movable parallel to itself in two directions at right angles, a plurality of stops which when set up determine the positions into which these members move, a series of longitudinally movable rods by means of which the determining stops are set up, the ends of these rods being all grouped like a chess board in rows parallel in two directions and in one plane, a series of stops which until withdrawn respectively serve to inhibit in groups and individually the positioning of the parallel movable members, a series of longitudinally movable rods by means of which the inhibiting stops can be withdrawn these rods being disposed and grouped with the stop setting rods, a series of knives each adapted to reciprocate towards and between the withdrawing and grouped ends of the stop setting rods, keys by means of which these knives are actuated, a series of setting plates with each of which engages the stop setting rods in one of the parallel rows, a series of setting plates with each of which engages one of the rods operating the inhibiting stops, and key controlled means for sliding the setting plates whereby the ends of the rods carried there-

by are brought into the paths of the knives as set forth.

4. In a calculating machine the combination of a plurality of members each separately movable parallel to itself in two directions at right angles, a plurality of stops which when set up determine the positions into which these members move, a series of longitudinally movable rods by means of which the determining stops are set up, the ends of these rods being all grouped like a chess board in rows parallel in two directions and in one plane, a series of stops which until withdrawn respectively serve to inhibit in groups and individually the positioning of the parallel movable members, a series of longitudinally movable rods by means of which the inhibiting stops can be withdrawn these rods being disposed and grouped with the stop setting rods, a series of knives each adapted to reciprocate towards and between the grouped ends of these rods, keys by means of which these knives are actuated, a series of setting plates with each of which engages the stop setting rods in one of the parallel rows, a series of setting plates with each of which engages one of the rods operating the inhibiting stops, a rotatable shaft, a series of cams on this shaft each cam being operative to cause a setting plate to slide and bring the end of each rod carried thereby into the path of a knife when the latter is reciprocated, a plurality of denominational selecting keys, and means actuated by these keys whereby the cam shaft is rotated as set forth.

5. In a calculating machine the combination of a plurality of members each separately movable parallel to itself in two directions at right angles, means by which each of these members when moved indicates a product, a plurality of stops which when set up determine the positions into which these members move and the products indicated thereby, a series of longitudinally movable rods by means of which the determining stops are set up the ends of these rods being all grouped like a chess board in rows parallel in two directions and in one plane, a series of knives each adapted to reciprocate towards and between the grouped ends of the stop setting rods, keys by means of which these knives are actuated, key controlled means for shifting the ends of the stop setting rods in rows at right angles to the knives so as to bring the ends of the rods into the paths of the knives, mechanism for ascertaining the amount of the products indicated by the parallel moving members when positioned, and means for adding these products and presenting the total as set forth.

6. In a calculating machine the combination of a plurality of members each separately movable parallel to itself in two directions at

- right angles, means by which each of these members when moved indicates a product, a plurality of stops which when set up determine the positions into which these members move and the products indicated thereby, a series of longitudinally movable rods by means of which the determining stops are set up, the ends of these rods being all grouped like a chess board in rows parallel in 10 two directions and in one plane, a series of knives each adapted to reciprocate towards and between the grouped ends of the stop setting rods, keys by means of which these knives are actuated, means for shifting the 15 ends of the stop setting rods in rows at right angles to the knives so as to bring the ends of the rods into the paths of the knives and mechanism for ascertaining the amount of the products indicated by the parallel moving 20 members when these are positioned, adding together the products of like nature ascertained from the positioned members by the said mechanism, and presenting the total as set forth.
- 25 7. A calculating machine including in combination, a plurality of members each separately movable in two directions within a plane, a plurality of movable stops for determining the positions into which these 30 members move, and means for adjusting the stops comprising a plurality of movable knives or plungers and a plurality of rods for operatively connecting the plungers and stops, said rods being shiftable to 35 inoperative position.
8. A calculating machine including in combination, a plurality of members each separately movable in two directions within a plane, a plurality of movable stops for 40 determining the positions into which these members move, and means for adjusting the stops comprising a plurality of rods movable relatively to the stops and in constant engagement therewith, and second means for 45 selectively moving said rods relatively to the stops.
9. A calculating machine including in combination, a plurality of members each separately movable in two directions within 50 a plane, a plurality of movable stops for determining the positions into which these members move, and means for adjusting the stops comprising a plurality of rods having cam surfaces thereon, the cam surfaces of 55 each rod being movable into engagement with the corresponding stop to move the same and second means for selectively moving said rods.
10. A calculating machine including in 60 combination, a plurality of members each separately movable in two directions within a plane, a plurality of movable stops for determining the positions into which these members move, and means for adjusting 65 the stops comprising a plurality of rods

engaging the stops, setting plates for shifting the rods, and devices for moving the setting plates.

11. A calculating machine including in combination, a plurality of members each 70 separately movable in two directions within a plane, a plurality of movable stops for determining the positions into which these members move, a rod engaging each stop for adjusting the same, setting plates for shifting the rods, cams for operating the setting plates and reciprocable members for operating the rods.

12. A calculating machine including in combination, movable product members, 80 means for moving said members and returning them to original position, stops for determining the extent of movement of said members, and means for operating the stops including setting plates, cams for operating 85 the setting plates, and key controlled means for operating the cams.

13. A calculating machine including in combination, sets of stop setting rods arranged in horizontal planes with one end 90 of each rod lying in a vertical plane passing through the corresponding ends of the other rods, reciprocable key controlled means for moving the rods longitudinally, and key controlled cams for moving the rods laterally out of the path of said first mentioned means.

14. A calculating machine including in combination, sets of stop setting rods arranged in horizontal planes with one end of 100 each rod lying in a vertical plane passing through the corresponding ends of the other rods, reciprocable key controlled means for moving the rods longitudinally, a plurality of cams rotatable about a vertical axis and 105 operatively connected to said rods for shifting said rods laterally, and key controlled means for rotating said cams.

15. A calculating machine including in combination, a plurality of stops, members 110 for setting said stops, means adapted to move said members to set said stops, and means for selecting the members to be moved by said means comprising setting elements, cams for moving said elements, a spring operatively connected to said cams and normally tending to operate them, and a key controlled escapement regulating the movements of said cams under the influence of 115 said spring.

16. A calculating machine including in combination, a plurality of stops, and selective mechanism for setting the stops comprising a plurality of cams rotatable about a fixed axis, a spring for normally rotating 125 the cams, and a key controlled escapement controlling the movement of said cams.

17. A calculating machine including in combination, a plurality of members each movable in two directions in a plane, a 130

plurality of stops which when set up determine the positions into which these members move, a series of longitudinally movable rods by means of which the determining stops are set up, the ends of the rods being disposed in a plane, a series of plungers each adapted to reciprocate towards and between the grouped ends of the stop setting rods, keys for actuating the plungers, and key controlled means for shifting the stop setting rods in rows.

18. A calculating machine including in combination, a plurality of stops and selective mechanism for setting the stops comprising, a rotatable shaft, a series of cams on the shaft, a spring actuated sliding plate carrying a toothed rack, a pinion on the cam shaft which engages this rack so that the shaft can be rotated by the sliding of the plate, a plurality of denominational selecting keys each of which when operated releases the sliding plate and determines the extent of its movement, and means for holding the cam shaft in the position into which it has been rotated after the operation of a denominational selecting key as set forth.

19. A calculating machine comprising in combination, a plurality of members each separately movable in two directions in a plane, a plurality of stops movable into the path of said members to limit their movements respectively, a series of longitudinally movable rods by means of which the determining stops are set up, the ends of these rods being grouped in rows parallel in two directions, a series of stops which until withdrawn respectively serve to inhibit in groups and individually the positioning of the movable members, a series of longitudinally movable rods by means of which the inhibiting stops can be withdrawn, and key controlled means for selecting and operating said rods.

20. A calculating machine comprising in combination, a plurality of members separately movable in a plane in two directions, and means for determining the positions into

which these members may be moved, including a plurality of stops for the members, a series of longitudinally movable rods by means of which the determining stops are set up, a series of stops which until withdrawn respectively serve to inhibit in groups and individually the positioning of the members, a series of longitudinally movable rods by means of which the inhibiting stops can be withdrawn, these rods being disposed and grouped with the stop setting rods, and key controlled means for operating the rods.

21. A calculating machine comprising in combination, a series of movable product plates, means by which each of these members when moved indicates a product, key controlled means for moving the plates to predetermined positions, and mechanism for ascertaining the amount of the products indicated by the product plates when these are positioned and presenting the total, said mechanism including, a series of unit mechanisms each of which is operative to add together the products of like nature ascertained from the positioned product plates, and a series of rotatable members respectively actuated by the unit mechanism.

22. A calculating machine comprising in combination, a plurality of members each movable in two directions within a plane, means associated with each member for indicating a product when the member is moved, mechanism for ascertaining the amount of the products indicated by the members when these are positioned, for adding together the products of like nature ascertained from the positioned members by the said mechanism, and for presenting the total, means for moving the members into indicating position, and mechanism for returning the members to inoperative position.

In testimony whereof I have signed my name to this specification.

FRANCES MAUD RUSSELL-CLARKE,
Sole Executrix of Edward Russell-Clarke, Deceased.
